UNITED STATES PATENT OFFICE.

CHARLES M. COTT, OF COLUMBUS, OHIO.

INDEX.

1,216,215.

Specification of Letters Patent. Patented Feb. 13, 1917.

Application filed June 25, 1914. Serial No. 847,361.

To all whom it may concern:

Be it known that I, CHARLES M. COTT, citizen of the United States, residing at Columbus, in the county of Franklin and State of Ohio, have invented certain new and useful Improvements in Indexes, of which the following is a specification.

This invention relates to indexing devices, and it has for its object, the provision of an improved index, constructed and arranged to take care of a maximum number of names in a minimum amount of space. The advantages of the index forming the subject matter of the present invention will be more clearly appreciated if some of the conditions to be met are clearly understood.

Because some names occur much more frequently than others and because it is not possible to tell in advance just how frequently any given name is going to occur, it has been found in the indexing systems heretofore employed, that some of the names over-run the spaces devoted to them, while other spaces remain unfilled and are wasted. The mere waste of space or paper is of small importance, but the unnecessary multiplication of volumes is of grave importance, and it is therefore, highly desirable to provide an indexing system which will be to a certain extent elastic, to prevent the over-running of names, but which will, at the same time, reduce wasted space to the minimum.

It is further, highly desirable to render the initial index (that is, the page to which the searcher first turns), as simple and clear as possible, to thereby avoid confusing the person making the search. An index constructed in accordance with the invention is made up of any desired number of volumes, each of said volumes containing one or more groups of pages devoted to such letters of the alphabet as may be found desirable.

Each of these groups is made up, first, of an index page, second a plurality of mixed group pages, and third, a plurality of surname and given name group pages. These three kinds of pages combined, constitute a unit, and there may be as many of these units as is necessary to take care of the entire alphabet.

In order to make clear the use of the index, I have illustrated in the accompanying drawings, the several pages described. In the drawing Figure 1 illustrates one of the index pages, Fig. 2 illustrates one of the

mixed group pages, and Fig. 3 illustrates one of the surname and given name group pages. All of these pages, it will be seen, relate to one unit, and the unit in this case covers those surnames beginning with A or B. It is thought that the use of the index shown in Fig. 1 will be apparent from an inspection of the same. However, it may be stated that if the name sought to be found is Annie Anderson, the letter 5 will indicate that the page number is to be found in the horizontal column bearing such letter, and the letter 6 will indicate that the page number upon which the name will be found is that page number indicated at 7, or in other words, at the intersection of the horizontal column in which the character 5 is found with the vertical column in which the character 6 is found. In this case the page number is 1.

This carries us to Sheet 2 of the drawings, which is a representation of the page 1, to which we are thus directed by the index shown in Fig. 1. This page 1 is sub-divided by a horizontal line 8, to constitute an upper space 9, and a lower space 10. The upper space is ruled horizontally at 11 and vertically at 12, to provide name columns 13, initial columns 14 and index page columns 15. In addition, printed matter 16 appears somewhere in space 9, the exact location being immaterial. This printed matter is for the purpose of making clear the fact that the space 9 receives those names which are either known to occur so frequently as to justify their being entered immediately in space 9, or else have demonstrated by the frequency of their occurrence that they should be so entered, and the manner in which the names demonstrate the frequency of their occurrence will be presently set forth. While I prefer to place the matter 16 and matter 25, hereinafter referred to, upon page 1, it is apparent that it may be omitted if desired, because with the principle understood, the method of indexing may be carried out without such printed matter.

The space 10 is horizontally ruled and at given intervals is sub-divided by heavier horizontal lines 17 to constitute mixed group spaces 18, 19, 20, 21, 22, 23 and 24. The reverse side of page 1 may be and preferably is ruled in like manner to constitute these mixed group spaces, but the illustration in Fig. 2 is sufficient to show the principle of

the invention and the reverse side of page 1 is accordingly not illustrated.

Somewhere in space 10 printed matter 25 appears, which directs the searcher to search for the name wanted in the mixed group spaces if such name is not found in space 9. Fig. 3 shows one of the surname and given name group pages and its use will appear from the description of the method of use of the index which now follows:

Assuming that the name is Annie Anderson, the searcher is directed to page 1 (see Fig. 2), as hereinbefore described, and following the direction of printed matter 16, 15 looks first in space 9 and finds that the names A. Anderson are to be found upon index page 146. The reason that the term "index" page is here used is to make it clear that this number 146 refers to one of the 20 pages of the unit of the index, which page is illustrated in Fig. 3, and not the page of the record book, this being obtainable as to the name A. Anderson together with all other necessary data, by turning to the 25 designated page 146 of the index. Turning now to this page, the searcher finds all of the names Anderson in which the given name begins with A. Suppose, however, that the name desired is Albert Albright, 30 the index shown in Fig. 1 will again direct the searcher to page 1 where the name, Albright, will be found in the mixed group space 21. The reason that this name, Albert Albright, is found in this space instead of 35 space 9 is that this name, Albright, has not up to this time occurred with sufficient frequency to justify its entry in space 9, but when the name Albright has occurred with sufficient frequency to fill all of the horizontal spaces, in space 21, then this name, 40 Albright, will be entered in space 9, and a page such as indicated in Fig. 3, will be devoted to the name Albright, and the number of this page will be entered in the index 45 page columns. This may be done in two ways. The clerk may write in the last line of space 22 "Continued on page 149," and may then make the entry as shown at 26, in Fig. 2; or alternatively, the clerk may write 50 across the names shown in space 23 "Transferred to page 150" (or any other unused page or portion of a page) and transfer the names contained in space 23 to page 150.

The principle involved is somewhat similar to that set forth in my co-pending application 814,204, filed January 29, 1914, but certain important advantages are obtained by the present index that are not present in the application named. One advantage that 55 may be mentioned is that the primary index, that shown in Fig. 1, contains no directions that would be likely to confuse a person unfamiliar with the system, but upon the contrary, a very clear and simple index, directs 60 the searcher to page 1, where in concise and

collected form are to be found both the mixed groups and the names to which surname and given name group pages have been devoted, and it is not necessary to turn back and forth to look for the name wanted, 70 which may be in a mixed group or may be in space 9, but by virtue of the arrangement hereinbefore described, the name is bound to be found upon the first page to which the searcher may be directed, though it may be 75 in space 9 or space 10. Time is thus saved, the index is simplified, and the likelihood of confusion in the mind of the searcher is prevented.

The invention is not necessarily limited to 80 subdividing space 10 into groups of names. Names may be written therein straight down the page as they occur and then when it is found that any given name is occurring frequently, such name may be entered in the 85 sub-index comprised in space 9 and a page such as shown in Fig. 3, may be devoted thereto in the manner hereinbefore set forth and after which such names may be canceled from space 10 or marked "Transferred." 90

Having described my invention what I claim is:

1. In an index, the combination with a page, of means for dividing said page into two divisions, means for dividing one of said divisions into a plurality of spaces, and means for subdividing said spaces so that said division comprises a series of groups of spaces of a predetermined limited capacity for the reception of names, the other of said divisions bearing matter adapting it to constitute an index for names overrunning said groups of spaces. 95

2. The combination with a page horizontally ruled to form an upper and lower division, of additional ruling dividing one of said divisions into a series of groups of spaces of a predetermined limited capacity, and ruling and indicia arranged within the other of said divisions adapting it to constitute an index for the names overrunning 105 said groups of spaces. 110

3. An indexing unit, devoted to letters of the alphabet and comprising a primary index, a page divided by ruling into two divisions, one of said divisions being further subdivided by ruling and bearing suitable indicia to constitute a series of groups of name receiving spaces, and the other of said divisions being so ruled and designated as 115 to constitute a secondary index for the reception of names of frequent occurrence and such names as overrun the mixed group spaces, and a page ruled and designated for the reception of surname and given name 120 groups and to which latter pages said secondary index relates. 125

4. In an index, the combination with a page ruled to comprise two divisions, one of which divisions bears matter adapting it 130

to receive names alphabetically falling thereto as they occur, and the other of which bears matter adapting it to constitute an index for those names occurring most frequently in the first named division, of an additional page to which said last named index relates.

5. In an index, a page ruled horizontally to divide it into two divisions, the lower of which divisions is ruled to divide it into a series of groups of spaces of a predetermined limited capacity bearing matter adapting them for the reception of names alphabetically falling thereto as they occur, and the other of which bears matter adapting it to constitute an index for those names occurring most frequently in the first named division, the name receiving portions of the index lying in vertical alinement with the said groups of spaces, whereby the names in the index and the names in said groups of spaces are brought into vertical alinement with each other.

6. The combination with an index page bearing page numbers, of pages corresponding to said numbers, said pages being ruled to subdivide them into two main divisions, one of said divisions being ruled and designated to divide it into a plurality of groups of name spaces of a predetermined limited capacity and bearing matter indicating that such names as are not found in said spaces are to be found in the other division of said page.

7. A page horizontally ruled to divide it into two divisions, one of which is further horizontally and vertically ruled to divide it into a plurality of vertical columns and a plurality of horizontally arranged groups of spaces of a predetermined limited capacity, the other of said divisions being vertically and horizontally ruled and bearing matter adapting it to constitute an index for such names as overrun the name receiving spaces of the first named division, said page bearing matter directing the searcher to search among the names in the groups of spaces if the name wanted is not found in the index in the other division of the page.

8. An index comprising a page ruled to divide it into two main divisions, one of said divisions being ruled to subdivide it into a plurality of groups of spaces of a predetermined limited capacity and the other of said divisions being ruled and designated to form name receiving columns, given name initial columns and index page columns, said page bearing matter directing the searcher to search for the name wanted in said first named division if said name does not appear in the other division.

9. An indexing unit devoted to a letter or letters of the alphabet and comprising first, a primary index indicating the pages

upon which the name desired is to be found, second, a page so indicated which page is ruled to divide it into two main divisions, one of said divisions being further ruled to form a plurality of groups of spaces of a predetermined limited capacity in which names are indexed as they occur, and the other of said divisions being ruled and designated to constitute an index serving to receive such names as overrun the groups of spaces, third, a page to which said index relates.

10. An indexing unit devoted to a letter or letters of the alphabet and comprising first, a primary index indicating the pages upon which the name desired is to be found, second, a page so indicated which page is ruled to divide it into two main divisions, one of said divisions being further ruled and designated to form a plurality of groups of spaces constituting a group index in which names are indexed as they occur, and the other of said divisions being ruled and designated to constitute an index serving to receive such names as overrun the groups of spaces, third, a page to which said last named index relates, said first named division bearing matter directing the searcher to search for the name wanted in the last named index if said name is not found in said group index.

11. An index comprising a page ruled horizontally to divide it into two main divisions, said page being ruled vertically to constitute a main column which extends through both of said divisions, one of said divisions being horizontally ruled to form a plurality of groups of spaces of a predetermined limited capacity and bearing matter directing the searcher to search in said spaces for the name wanted, if said name is not found in the other division, said last named division being ruled and designated to constitute an index for the names which are entered therein as they overrun the groups of spaces as herein described.

12. In an indexing system, a part ruled and designated to constitute a primary index, for the reception of such names as occur frequently, and a part ruled and designated to adapt it to constitute a secondary index for such names as occur with lesser frequency, said secondary index being of predetermined limited capacity and said primary index serving to receive such names as overrun the limited capacity of the secondary index.

13. In combination with a page horizontally ruled to form an upper and lower division of additional rulings dividing one of said divisions into a series of spaces of a predetermined limited capacity properly designated for the reception of names and additional rulings and designations arranged within the other of said divisions

to arrange it to constitute an index for the names overrunning the spaces of the first named division.

14. In an index a page ruled horizontally to divide it into two divisions the lower of which division is further ruled and designated to divide it into a series of groups of spaces of a predetermined limited capacity for the reception of names alphabetically falling thereto as they occur and the other of which divisions is ruled and designated for the reception of those names that occur most frequently in the first named divi-

sion the name receiving portions of the index lying in vertical alinement with said 15 groups of spaces whereby the names in the index and the names in said groups of spaces are brought into vertical alinement with each other.

In testimony whereof I affix my signature 20 in presence of two witnesses.

CHARLES M. COTT.
